UNITED STATES PATENT OFFICE.

GUSTAV LEHLBACH, OF NEWARK, NEW JERSEY.

RAILWAY-FROG.

SPECIFICATION forming part of Letters Patent No. 323,585, dated August 4, 1885.

Application filed April 11, 1885. (No model.)

To all whom it may concern:

Be it known that I, GUSTAV LEHLBACH, a citizen of the United States, residing at Newark, in the county of Essex and State of New Jersey, have invented certain new and useful Improvements in Railway-Frogs; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The invention relates more particularly to the construction of a device to be used where one rail upon railroad tracks has to cross another, which crossing is at present usually accomplished by means of a frog; and the improvements are set forth in the following specification and accompanying drawings, in which—

Figure 1 represents the plan of the improvement. Fig. 2 represents a section upon the line A B of Fig. 1. Fig. 3 represents a section upon the line C D of Fig. 1.

In Fig. 1 the different parts of the improvement are designated by the following letters: M designates the rails of the main track; T, the rails of the turn-out track which crosses the rail of the main track. F are iron or steel frog-bars. H are hinges suitably fastened to the aforesaid frog-bars F F. P are iron chairs to receive the ends of the turn-out rails, and to which the hinges H H are also connected, and upon which the ends of the frog-bars F F also rest and move. I are iron guide-plates, upon which the frog-bars F F slide when moved, and upon which they also have a bearing when in position for the turn-out track. L are lever-bars and connecting-rods suitably fastened to the frog-bars F F at K K, and so arranged that motion can be given to the frog-bars F F to change their positions to those indicated by the dotted lines in the figure. Q are connecting-rods leading to the switch. R are the cross-ties; S, a spring permitting a movement of about six inches.

In Fig. 2, M designates the rail of the main track; F, the frog-bar. In Fig. 3, M designates the rail of the main track; F, the frog-bar; I, a guide-plate, and R the cross-tie.

The objects of the invention are, first, to avoid the cutting of the main-track rail; second, to furnish an unbroken and continuous bearing for the wheels upon the turn-out track as well as upon the main track.

The cutting of the main-track rail is avoided by the raising of the frog-bars F F, so that the tops of these bars are about two inches above the top of the main-track rail, as shown in Figs. 2 and 3, thereby permitting the flanges of the wheels to pass over the main-track rail without touching it, the rails of the turn-out track T T being gradually raised to meet the elevation of the frog-bars F F.

The unbroken and continuous bearing upon the turn-out track is effected by the frog-bars, which meet upon the top of the main-track rail sufficiently close to make the bearing practically unbroken and continuous, being supported at that point by the main-track rail upon which they rest, and also being held in this position by the lever-bars L. The frog-bars F F are also slotted so as to fit around the head of the main-track rail, as shown in Fig. 2, so that when the frog-bars are set for the turn-out track they will be firmly held in their positions.

In Fig. 1 the frog-bars are in position for the turn-out track to cross the main track at the angle shown, and the dotted lines indicate the positions which are occupied by the frog-bars F and the lever-bars L when set to leave the main track clear and intact.

By means of the rods Q Q in Fig. 1, which are suitably connected with the mechanical arrangement for moving the switch, any movement of the switch will at the same time give the requisite corresponding movement to the frog-bars F F.

In case the frog-bars should by mistake be set for the turn-out track when it was intended to have left the main track clear, a spring, as S, or its equivalent is provided and arranged so that the wheels of a train upon the main track will press the frog-bars F F aside and thus allow the free passage of the train upon the main track past the frog-point in either direction.

The arrangement and operation of the spring S are as follows: Said spring is placed in an iron frame, and at one end one of the lever-bars L is fastened to the frame, and at the other the

lever-bar L can move freely through a hole in the head of the iron frame and press upon the spring by the intervention of suitable washers, as indicated in the drawings. The proper strain 5 with which it is desired to press the bars F against the main rail is put upon the spring when it is placed in the frame, and when a pressure greater than this is exerted upon the spring by reason of the pressure of passing 10 wheels against the sides of the frog-bars F, the spring S is compressed still more, thus allowing the frog-bars to open without breaking any of the parts, as will be understood.

I am aware that it is not new to adapt the 15 ordinary railroad-rail as parts of an arrangement by which the rail of a turn-out track is passed over the main-track rail without cutting such main rail; but the shape of an ordinary railroad-rail does not permit this to be 20 done with safety and durability. I have therefore devised the movable frog-bars F, as shown in the drawings, constructed from rectangular bars of metal and mitered where they come together upon the top of the main rail, and 25 slotted or grooved to fit around the head of the main rail for the purpose of holding them firmly in position, as shown. Said frog-bars are also arranged in a horizontal position and move in the same plane, so that no break in 30 the grade of the crossing occurs upon the movable parts, as has been the case heretofore.

Having thus described my invention, I claim—

1. The combination, with the rails of a railroad-track, of frog-bars, as F F, slotted or 35 grooved, as described, and means arranged to operate in connection therewith, for the purposes set forth.

2. The combination, with the rails of a railroad-track, of frog-bars, as F F, and a system 40 of levers, as L, arranged and operating for the purposes set forth.

3. The combination, with the rails of a railroad-track, of frog-bars, as F F, a system of 45 levers, as L, and a spring, as S, or equivalent means, arranged and operating in connection therewith, for the purposes set forth.

4. The combination, with the rails of a railroad-track, of frog-bars, as F F, a system of 50 levers, as L, a spring, as S, or equivalent means, and rods, as Q, connecting the levers, as L, with the mechanism for moving the switch, and adapted to be operated thereby, for the purposes set forth.

In testimony that I claim the foregoing I 55 have hereunto set my hand this 10th day of April, 1885.

GUSTAV LEHLBACH.
